DESIGN FOR A DRESS

Mary G. Strangard, New York, N. Y.

Application December 30, 1937, Serial No. 73,972

Term of patent 3½ years

To all whom it may concern:

Be it known that I, Mary G. Strangard, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein.

I claim:

The ornamental design for a dress, substantially as shown.

MARY G. STRANGARD.
